UNITED STATES PATENT OFFICE

150,176

DESIGN FOR A CHAISE LONGUE

William W. Vincent, Jr., Kenosha, Wis., assignor
to The Vincent-McCall Company, Kenosha,
Wis., a corporation of Wisconsin

Application November 22, 1946, Serial No. 135,024

Term of patent 14 years

(Cl. D15—11)

To all whom it may concern:

Be it known that I, William W. Vincent, Jr., a citizen of the United States, residing in the city of Kenosha, county of Kenosha, and State of Wisconsin, have invented a new, original, and ornamental Design for Chaise Longue, of which the following is a specification, reference being had to the accompanying drawing, forming part thereof and showing the new design in perspective, both sides of the chaise longue being alike.

I claim:

The ornamental design for a chaise longue, substantially as shown and described.

WILLIAM W. VINCENT, JR.
